GOLF PRACTICING APPARATUS

Basil C. Taylor, Detroit, Mich.

Application September 1, 1948; Serial No. 47,209

3 Claims. (Cl. 273—35)

1

This invention relates to a golf practicing apparatus and has for one of its objects to provide a practical, instructive and interesting device of this character.

Another object of the invention is to provide a golf practicing apparatus, employing a captive ball, so that the device can be used indoors or outdoors.

The foregoing as well as other objects and advantages will be made more apparent as this description proceeds, especially when considered in connection with the accompanying drawings wherein:

Figure 1 is an enlarged fragmentary sectional view, with certain other parts being broken away, showing a support or mounting for the captive ball;

Figure 2 is a fragmentary elevational view, with one of the parts in section, showing a modified form of means for rendering the ball captive to its support;

Figure 3 is a sectional view taken on the line 4—4 of Figure 2;

Figure 4 is a fragmentary sectional view showing another modified means for attaching the ball to its support;

Figure 5 is a detailed view of the tee upon which the ball is mounted before being struck.

Referring to the drawings the apparatus consists of a platform 10 which may be formed of any suitable material, as for instance, plywood or the like.

The reference character 13 designates the support for the golf ball which support will be more fully described later. The golf ball 14 is attached to the support 13 and rendered captive by a link or connector indicated generally by the reference character 15, several forms of which will be described more in detail hereafter.

It will be noted that the support 13 is in the form of a mooring mast. It may be and preferably is formed of a casting having an upright conical-shaped portion 22 terminating at the upper end in a thickened portion 23 and at its lower end in a horizontally disposed annular flange 24. This mooring mast is secured to the platform 10 by means of bolts, or the like, 25 extending through the flange 24 and a mat 26 of soft material, such as rubber of the like, is interposed between the mooring mast and the platform 10, to minimize noise when the ball is struck and to provide a limited degree of resilience between the mooring mast 13 and the platform 10. For the purpose of strengthening the structure, webs or

2

ribs 27 may be provided at the juncture of the conical wall 22 and the annular flange 24.

A post 28 is rigidly secured in the thickened portion 23 of the mast and extends upwardly therebeyond. This post may be provided with serrations 29 to assist in rigidly securing the post 28 to the mast. Mounted on the projected end of the post 28 are a pair of bearing members 30, the inner sleeves 30a of the bearing members 30 rigidly fixed to the post 28 by means of a cap-nut 31 which is engaged on the threaded end of the post 28. A lock washer 32 is interposed between the nut 31 and the upper inner sleeve member 30a of these bearings. By removing the nut 31 the bearing members and the parts supported thereby may be removed, if desired, for repair or replacement.

The outer sleeve members 30b of the bearings are adapted to be engaged by the end of the link or connector 15 which in the form of construction being described is formed of spring wire. In forming this connection, the end of the wire link or connector 15 is looped twice around the sleeve members 30b as indicated at 33 and the free end is then wound around the main portion of the link as indicated at 34 to insure against disengagement of the link when the ball is struck.

At some place in its length, the link 15 is formed into a tension spring 35 and the free end is provided with a hook or other enlargement 36 which is embedded in the ball by molding the same therein when the ball is formed. The tension spring 35 will provide a degree of resilience in the connector or link 15 which takes up the first force of impact of the blow on the ball.

It will be obvious from the description thus far that when the ball is struck, for instance by a right hand golfer, it will swing freely in a clockwise direction around the post 28 of the mooring mast 13, the actuating sleeves 30b of the bearings moving with the link or connector 15 during the swinging movement.

In Figures 2 and 3 another form of link or connector is illustrated. In this form of construction, the link is formed of two parts, 37 and 38. The part 37 is provided with loops 33 which extend around the bearing members as described in connection with the form of construction illustrated in Figure 1. The free end of the part 38 is imbedded in the ball 36 as previously described. In this form of construction, the spring portion of the link is a compression spring. In order to accomplish this, the end of the part 37 is formed into a compression spring 37a and the part 38 is formed into a compression spring 38a. The ends

of the parts 37 and 38 overlap and their respective spring portions 37a and 38a lie on opposite sides of a washer or abutment 39. This washer or abutment 39 shown in detail in Figure 4 is provided with a centrally arranged elongated slot 40 through which the straight portions of the link parts 37 and 38 extend. When the ball 14 is struck the tendency of the link member to elongate is resisted by these compression springs as will be obvious.

In Figure 4, another form of link or connector is illustrated. In this form of construction, the link consists of a flexible cord 41 impregnated with rubber which fills the interstices of the cord and forms a sleeve or rubber wall 42 on the outside. The end of the flexible sleeve may be enlarged as shown at 43 and imbedded in the ball 14 when the latter is molded or formed. The other end of the link has molded thereto a bearing cap 44 in the form of an annular sleeve which is shown as substantially L-shaped in cross-section. In this form of construction, only a single bearing 45 need be used and the bearing cap 44 is engaged with the outer sleeve 45a of the bearing by a press fit. The cord 41 of the link or connector may be formed of nylon thread, fibre glass or any other suitable, flexible material which will have sufficient strength to resist the force of the blow upon the ball.

In using the device, the ball is placed upon a tee 46 such as illustrated in Figure 5. This tee may be in the form of a sleeve formed of rubber or other suitable flexible material. It is permanently mounted in the platform 10. One convenient means for mounting the tee in place consists of providing a plug 47 secured within the interior of the sleeve-like member and in cementing the lower end of the tee in an opening 48 formed in the platform 10.

It is obvious that various changes may be made in the arrangement, combinations and construction of the various parts of my improved apparatus without departing from the spirit of my invention, and it is my intention to cover by my claims such as may be reasonably included within the scope thereof.

What I claim as my invention is:

1. A golf practicing apparatus comprising a base adapted to be mounted in fixed position, a vertically disposed shaft fixedly mounted in said base, a pair of bearing members mounted on said shaft, means securing said bearing members against movement axially of said shaft, said bearing members including portions adapted to rotate relative to said shaft and having spaced axially presenting flanges defining an annular and

radially outwardly opening channel, an arm comprising a wire having a plurality of turns at its inner end received in and having a combined axial extent substantially filling said channel between said flanges, and a golf ball secured to the outer end of said arm.

2. A golf practicing apparatus comprising a base adapted to be mounted in fixed position, a vertically disposed shaft fixedly mounted in said base, a pair of bearing members mounted on said shaft, means securing said bearing members against movement axially of said shaft, said bearing members including portions adapted to rotate relative to said shaft and having spaced axially presenting flanges defining an annular and radially outwardly opening channel, an arm comprising a wire having a plurality of turns at its inner end received in and having a combined axial extent substantially filling said channel between said flanges, the end portion of said wire making a plurality of turns about the main portion of the wire outwardly of said first mentioned turns for securely anchoring said end portion, and a golf ball secured to the outer end of said arm.

3. A golf practicing apparatus comprising a base adapted to be mounted in fixed position, a vertically disposed shaft fixedly mounted in said base, bearing means rotatably supported on said shaft and having spaced axially presenting flanges defining an annular radially outwardly opening channel, an arm comprising a wire having a plurality of turns at its inner end received in and having an axial extent substantially filling said channel between said flanges, and a golf ball secured to the outer end of said arm.

BASIL C. TAYLOR.
